UNITED STATES PATENT OFFICE.

DAVID E. HALE, OF KANSAS CITY, MISSOURI, AND JOHN E. McCORMICK, OF KANSAS CITY, KANSAS.

TOOL FOR BRICKMASON.

1,342,439.

Specification of Letters Patent.

Patented June 8, 1920.

Application filed February 17, 1919. Serial No. 277,617.

To all whom it may concern:

Be it known that we, DAVID E. HALE and JOHN E. McCORMICK, citizens of the United States, residing at Kansas City, in the 5 counties of Jackson and Wyandotte and States of Missouri and Kansas, respectively, have invented certain new and useful Improvements in Tools for Brickmasons, of which the following is a specification.

10 Our invention relates to tools to be employed by brickmasons in striking out mortar from joints between bricks as they are laid in courses to form the outer face of a wall, and one object is to provide a 15 tool of this character having interchangeable striker elements to fit joints of different widths and adjustable to strike or rake out the mortar in said joints to different depths.

20 A further object is to provide a tool of this character with interchangeable troweling elements to fit into the different size joints, smooth the surface of the mortar and clean out all loose mortar in said joints.

25 Other objects will hereinafter appear, and in order that the invention may be fully understood, reference will now be made to the accompanying drawings in which:

30 Figure 1 is a side elevation of the tool partly broken away to show a pocket therein.

Fig. 2 is a plan view of the tool.

Fig. 3 is an inverted plan view of the tool.

35 Fig. 4 is an inverted detail perspective view of a troweling element constituting a part of the invention.

Fig. 5 is a detail of a pin employed in adjusting the striker elements longitudinally.

40 In carrying out the invention, I employ a handle 1 provided at one end with an angular extension 2 and at its upper side with a recess 4 having an internally threaded plate 6 firmly secured to the bottom of the 45 recess by suitable means, such as screws 8. The upper side of the handle 1 is also provided with wear-plates 10 removably held in place by suitable means, such as screws 12, so that said plates can be replaced by 50 others when worn out.

The underside of the handle 1 is provided with a pocket 14 to hold the detachable parts of the tool as will hereinafter appear. Said

55 pocket 14 is normally closed by a slidable cover 16 having dove-tail ends 18 to fit into corresponding grooves 21 in the handle 1. As disclosed by Fig. 3, the cover 16 tapers 60 toward its rear side, so that it cannot be pushed clear through the dove-tail grooves, but must be inserted and removed from the front side thereof. A turn-button 20 is pivoted to the handle 1 to normally hold the cover 16 from sliding out between the dove-tail grooves 21.

22 designates a striker element which is 65 threaded into the plate 6 and locked therein from accidental displacement by a jam-nut 24. The outer end of the striker element 22 has a conical head 26 to fit into the joints 70 between the bricks and strike or rake out the mortar to any desired depth, such depth being determined by the distance to which the upper surface of the head 26 projects beyond the upper surface of the wear-plate 10. The striker element 22 is adjusted in 75 or out as desired by inserting the pin 28 in the transverse hole 30 in the head 26 for the purpose of screwing the striker element 22 inwardly or outwardly as required. Any 80 number of interchangeable striker elements 80 may be employed with heads of different diameters to fit into different sized joints.

The angular extension 2 is shod with a troweling element 32 having a long surface 34 and a short surface 36 extending at an 85 obtuse angle to said long surface 34. The troweling element 32, which is permanently secured to the angular extension 2, is of such width as to enter the narrowest joints 90 between the bricks and smooth the surface 90 of the mortar in said joints. When the bricks are laid with wider joints, interchangeable troweling elements of different widths as 38 are employed to fit such wider joints. Said troweling element 38 has a 95 long marginal flange 37 and a short marginal flange 39, which fit snugly over the corresponding surfaces 34 and 36, respectively, of the troweling element 32. The troweling element 38 also has spacing lugs 40 and 42, 100 to bear against the adjacent side of the angular extension 2 to hold the edge 44 of the flanges 37 and 39 flush with the edge 46 of the troweling element 32. The lug 40 has a hole therein for the passage of a bolt 105 54 provided with a thumb nut 56 which co-

acts with the bolt in holding the troweling element 38 firmly in position on the troweling element 32. The long surfaces of the troweling elements are used in smoothing the mortar in the horizontal joints between the bricks while the short surfaces are used in vertical joints between the bricks. The point 35 at the juncture of the long and short troweling surfaces 34 and 36, respectively, can be employed to advantage in cleaning out surplus mortar in the corners of joints.

The depths to which the troweling elements enter the joints is regulated by a gage 48 which has surfaces 50 and 52 paralleling the troweling surfaces 34 and 36, respectively. Said gage 48 is held in place by suitable means such as the bolt 54 and the thumb nut 56, said bolt 54 passing through a slot 58 in the gage, so that the same may be adjusted toward or away from the troweling surfaces according to the depth to which they are to enter the joints between the bricks. A washer 60 is interposed between the head of the bolt 54 and the adjacent side of the angular extension 2 to protect the latter from wear by the former.

When the device is not in use the pin 28 and the interchangeable striker elements are carried in the pocket 14 so that they will always be at hand when needed.

From the foregoing description, it is apparent that we have produced a simple, inexpensive and efficient tool well adapted for the purposes intended, and while we have shown and described the preferred form of our invention, we reserve the right to make such changes in the construction, combination and arrangement of parts, as properly fall within the spirit and scope of the claims.

Having thus described our invention, what

we claim and desire to secure by Letters Patent, is:

1. A tool of the character described consisting of a handle provided at one end with an angular extension, an element on said extension provided with long and short troweling surfaces meeting in an acute angle, and a gage secured to one side of the angular extension and provided with long and short surfaces paralleling the corresponding surfaces of said element.

2. A tool of the character described consisting of a handle provided at one end with an angular extension, an element on said extension provided with long and short troweling surfaces meeting in an acute angle, a gage adjustably mounted at one side of the angular extension and provided with long and short surfaces paralleling the corresponding surfaces of said element, and means to secure said gage at any point of its adjustment.

3. A tool of the character described consisting of a handle provided at one end with an angular extension, an element fixed on said extension and provided with long and short troweling surfaces, a second element having long and short troweling flanges to fit over the corresponding surfaces of the first element, spacing means on one side of the second element to abut the adjacent side of the angular extension, a gage to fit against one side of the second element, and means to secure said gage and the second element in place.

In testimony whereof we affix our signatures in the presence of two witnesses.

DAVID E. HALE.
JOHN E. McCORMICK.
